UNITED STATES PATENT OFFICE.

JOHN J. CHAMBERLAIN, OF AKRON, OHIO, ASSIGNOR TO THE UNITED STATES STONE-WARE COMPANY, OF AKRON, OHIO, A CORPORATION OF OHIO.

PRESS.

Application filed November 11, 1924. Serial No. 749,147.

To all whom it may concern:

Be it known that I, JOHN J. CHAMBERLAIN, a citizen of the United States, residing at Akron, in the county of Summit, State of Ohio, have invented certain new and useful Improvements in Presses, of which the following is a specification.

This invention relates to presses for making various articles of plastic material such as clay, artificial stone compositions and the like.

The purpose of the invention, in general, is to provide a press of universal application to many different articles of stoneware including pottery, chemical ware and the like, and adapted rapidly and inexpensively to operate, to turn out articles in large quantities.

An important feature of the invention is the provision in a press of improved means so operating a die that the latter may be either reciprocated to form ordinary molded articles or reciprocated and also rotated to form hollow articles such as pottery.

Another important feature of the invention is the provision of a rotary table carrying a plurality of molds with which the die is adapted to cooperate and improved means for intermittently rotating the table and stopping it with a mold in proper alignment with the die, the said means being cooperatively connected to the die-operating means so that movement of the table is timed with respect to the die.

The foregoing and other objects will be better understood when the following detailed description is read in connection with the accompanying drawings, it being understood that the invention is not limited to the specific form thereof described and illustrated.

Of the accompanying drawings:

Figure 1 is a front elevation of a press embodying the invention;

Figure 2 is a right side elevation thereof;

Figure 3 is a section on line 3-3 of Figure 1;

Figure 4 is a detail plan of the table-rotating device;

Figure 5 is a detail side-elevation thereof;

Figure 6 is a detail front elevation thereof;

Figure 7 is a plan of a carboy stopper which is one of the many articles the press is adapted to form; and

Figure 8 is an elevation thereof.

Referring to the drawings, 10 is a stand or table having legs 11, 11 thereon. At its forward end the table 10 is cut away to provide an opening 12 through which extends a vertical shaft 13 carrying on its upper end a rotary table 14, the shaft 13 being rotatably mounted in bearings 15 and 16 in which it is supported by a projecting sleeve 17 on table 14 and adapted to ride on the upper surface of bearing 15 and by table-driving plate 18 riding on the upper surface of bearing 16. Bearings 15 and 16 are respectively supported by suitable beams 19 and 20, spanning legs 11 below the top of table 10.

The rotary table 14 carries a plurality, in this instance, four molds 21, 21 which in the drawings are shown as designed for molding carboy stoppers 22. The molds 21 are replaceable with other molds for molding other articles. For this purpose each mold 21 is formed with a projection 23 on its lower end adapted to seat in an aperture 24 in table 14 and to be secured therein by a set screw or the like, 25. In the bottom of each mold 21, an ejector plunger 26 is seated, the plunger being formed with a rod 27 extending downwardly through the projection 23 and through opening 12 so as to be engageable with a cam plate 28 so formed as to lift the ejector and consequently lift the completed article out of the mold after the die has operated thereon. Cam plate 28 may be secured on beam 19 for this purpose.

Movable toward and from the molds 21 as each is in a certain angular position over table 10 is a die 29 removably secured by set screws 30, 30 to a cross-head 31 reciprocable on vertical posts 32, 32 which are mounted on the table 10 and supported by brackets 33, 33 mounted on the rear of table 10. The dies 29 have projecting lips 29^a, 29^a extending downwardly therefrom and adapted to embrace the molds 21 to insure accurate positioning thereof beneath the die. The cross-head 31 preferably has a guard plate 31^a secured across the front thereof.

For operating the rotary table 14 and reciprocating the cross-head 31, the press is adapted to be driven from any suitable source of power by a pulley 34. The pulley 34 is secured on main drive shaft 35 on which are secured pinions 36, 36 for driving gears 37, 37. Gears 37 are secured on drive

shaft 38 on which is secured an eccentric disc 39 encircled by a strap 40. Formed on strap 40 is a pawl 41 arranged to ride on the upper surface of drive plate 18 which latter is provided with a plurality, in this instance, four pins 42, 42 projecting upwardly from its surface and on which are journaled case-hardened rollers 43, 43. Secured on one side of pawl 41 is a stop block 44. Secured on gears 37 are crank pins 45, 45 on which are pivoted connecting rods 46, 46 which are also pivoted on pins 47, 47 formed on cross-head 31.

In the making of pottery it is frequently necessary to rotate the die and to this end, instead of securing the die directly to cross-head 31 by set screws 30, it is preferably secured on the end of a floating shaft 48 rotatable in a bearing 49 in cross-head 31 and supported on the cross-head for reciprocating therewith by a collar 50 riding on the upper surface of bearing 49. Shaft 48 is supported vertically by a bearing 51 in a beam 52 spanning the upper ends of posts 32, the shaft 48 being vertically slidable in bearing 51. Keyed onto the shaft 48 is a bevel gear 53 adapted to ride on the upper surface of bearing 51 and adapted to be employed to drive shaft 48 in any of its positions, the latter having a key-way 53a extending throughout its length.

Gear 53 may be driven or not, as desired, by a bevel gear 54 secured on a shaft 55, journaled in bearing 56 formed in a bracket 57 which may be mounted on beam 52. Shaft 55 has a sprocket 58 secured thereon which may be driven by a chain (not shown), driven by a sprocket 59 on shaft 35.

In operation, for making articles such as the carboy stoppers 22, the chain over sprockets 58 and 59 is not employed. The pulley 34 is driven, thus driving shaft 38 which operates eccentric 39 and pawl 41 forwardly, the latter riding into engagement with a roller 43 thus driving plate 18 and rotating table 10 until the limit of the forward movement of pawl 41 is reached. Block 44 engages a succeeding roller 43 and positively stops rotation of the table and prevents accidental rotation thereof until pawl 41 rides back over the next succeeding roller whereupon block 44 is moved out of the path of the rollers by eccentric 39 to permit the next rotation of the table.

While the table is being rotated, cranks 45 are operating cross-head 31 upwardly from its middle position and back downwardly thereto so that the die 29 is ineffective during this interval. As pawl 41 rides back over plate 18 and the next succeeding roller 43, and while the block 44 is preventing rotation of the table, the die advances downwardly into cooperation with one mold 21 which is positioned directly therebeneath due to the predeter-

mined relative positioning of rollers 43 with respect to the molds. After the material in the mold has been pressed into shape by die 29 and while the cross-head is rising to its middle position, the pawl 41 rides over and in back of the next succeeding roller 43 and as the shaft 38 continues to rotate the above described operations are repeated, the molds 21 being operated on in succession.

The material, such as clay, from which the article is formed, is placed in the molds prior to their passage under the die and the finished articles are ejected from the molds by engagement of plunger rods 27 with cam plate 28 as the molds come from under the die.

When molding hollow articles, for example, flower posts a die for forming the interior of the pot is used in place of die 29. A chain is then trained over sprockets 58 and 59 and gear 54 is thus caused to continuously rotate gear 53, shaft 48 and the die, the latter accordingly being rotated during the pressing action described above to form a smooth surface on the pottery.

Modifications of the invention may be resorted to without departing from the spirit thereof or the scope of the appended claims. While the mechanism is shown as adapted to manufacture specific articles of stoneware, it may be used in other branches of the clay industry as will be understood.

What is claimed is:

1. A machine of the class described comprising a rotary mold-carrying table, a die reciprocable toward and from said table, and means for rotating the table and reciprocating the die, said means comprising a rotating shaft, an eccentric on the shaft, a drive plate secured to the table, projections on the drive plate, a pawl formed on the eccentric strap and adapted to ride on said plate and to engage the projections, a stop plate also on the eccentric strap for engaging the projections, a cross-head for carrying the die, cranks on the shaft and connecting rods between the cranks and the cross-head.

2. A machine of the class described comprising a rotary mold-carrying table, a die reciprocable toward and from said table, and means for rotating the table and reciprocating the die, said means comprising a rotating shaft, an eccentric on the shaft, a drive plate secured to the table, projections on the drive plate, a pawl formed on the eccentric strap and adapted to ride on said plate and to engage the projections, a cross-head for carrying the die, cranks on the shaft and connecting rods between the cranks and the cross-head.

3. A machine of the class described comprising a rotary table, and means for imparting intermittent rotation to the table, said means comprising a continuously rotat-

ing shaft, an eccentric on the shaft, a pawl formed on the eccentric strap, a plate secured to the table and arranged so that the pawl will ride on the surface thereof, and spaced projections on the plate adapted to be engaged by said pawl.

4. A machine of the class described comprising a rotary element, and means for intermittently rotating said element, said means comprising a continuously rotating shaft, an eccentric disk secured on the shaft, an eccentric strap formed with a pawl and encircling said disk, a surface rotatable with said element and on which said pawl is adapted to ride, and spaced projections on said surface adapted to be engaged by said pawl.

5. A machine of the class described comprising a rotary element, and means for intermittently rotating said element, said means comprising a continuously rotating shaft, an eccentric disk secured on the shaft,

an eccentric strap formed with a pawl and with a stop and encircling said disk, a surface rotatable with said element and on which said pawl is adapted to ride, and spaced projections on said surface adapted to be engaged by said pawl and stop.

6. A machine of the class described comprising a rotary element, and means for intermittently rotating said element, said means including a continuously rotating shaft and a pawl eccentrically pivoted on said shaft.

7. In a press of the character described, a rotary table, molds spaced circumferentially about the table, a die reciprocating toward and from the surface of the table, means for intermittently rotating the table and approximately positioning the molds in succession under the die and means on the die for engaging the molds to accurately position the same thereunder.

JOHN J. CHAMBERLAIN.
